UNITED STATES PATENT OFFICE.

THOMAS J. WILLIAMS, OF UTICA, NEW YORK.

GUN.

1,113,723.

Specification of Letters Patent. Patented Oct. 13, 1914.

Application filed March 17, 1914. Serial No. 825,292.

To all whom it may concern:

Be it known that I, THOMAS J. WILLIAMS, a citizen of the United States, residing at Utica, in the county of Oneida and State of New York, have invented certain new and useful Improvements in Guns, of which the following is a specification.

This invention relates to a gun, and the principal object of the invention is to provide an improved trigger operating mechanism which will be mounted in the stock of the gun and thus be concealed. By having the operating mechanism concealed the danger of the gun being accidentally discharged is eliminated thus preventing danger of accidents.

Another object of the invention is to provide a trigger actuating mechanism which is very simple in construction and which is therefore not liable to easily get out of order.

Another object of the invention is to so construct the actuating mechanism that the same will be normally held in an inoperative position and returned to the inoperative position when pressure is removed from its plunger.

This invention is illustrated in the accompanying drawings wherein—

Figure 1 is a fragmentary view of a shot gun shown partially in elevation and partially in section; Fig. 2 is a sectional view taken along the line 2—2 of Fig. 1; Fig. 3 is a fragmentary bottom plan view of the stock of the shot gun; Fig. 4 is an elevation 35 of the plunger and casing in which the plunger is slidably mounted.

In the accompanying drawings the numeral 10 indicates the stock of the shot gun which is constructed in the usual manner and carries the barrel 11. This barrel is connected with the stock in the usual manner so that the gun may be broken and a shell placed in the breech of the barrel. The gun shown is of the hammerless type and is provided with a short trigger 12 which is mounted upon the pin 13 and is intended to release the mechanism for driving the plunger of the gun into the cap of the shell.

The mechanism for actuating the trigger 12 is shown very clearly in Figs. 1 and 2 and this is what forms the improved feature of the gun. In the stock 10 there is formed a chamber 14 from which there leads a passage-way 15 communicating with a smaller chamber 16 into which the trigger 12 extends. A piston 17 is slidably mounted in

the passageway 15 and is positioned to engage the trigger 12 so that when the piston is moved toward the chamber 16, it will move the trigger 12 to release the mechanism for driving the plunger of the gun.

A curved arm 18 extends from the piston 17 into the chamber 14 and is engaged by the free end of the leaf spring 19. A casing 20 is mounted in the chamber 14 and is provided with a slot 21 through which the pivot ear 22 extends. This pivot ear 22 extends from a plunger 23 which is slidably mounted in the casing 20 and is normally held in the position shown in Fig. 2 by means of spiral spring 24. The spiral spring 24 is mounted in the inner end of the casing 20 and is coiled about the reduced end of the plunger 23 and abuts against the abutment collar 25. At the outer end of the plunger 23 there is formed a head 26 which is positioned in the socket 27 and serves to limit the inward movement of the plunger. By placing the finger against the head 26, the plunger can be moved inwardly against the tension of the spring 24 and will move the piston 17 toward the chamber 16 due to the fact that the curved arm 18 is pivotally connected with the pivot ear 22. In order to protect the plunger 23 a sliding plate 28 has been provided, the plate being mounted in a track formed in the gun stock and provided with a projection or pin 29 so that the plate may be slid in the track to uncover the plunger 23 when desired.

In the operation of this gun, the shell is placed in the barrel 11 and the gun then closed. In all guns of the hammerless type, the mechanism for driving the shell engaging plunger is set by simply closing the breech with the shell in place. It is therefore not necessary to illustrate this mechanism as it may be of any desired type. The gun is now ready for use and can be discharged by simply pressing the plunger 23 thus moving the plunger 23 inwardly and moving the piston 17 toward the chamber 16. As the piston 17 moves toward the chamber 16, it moves the trigger 12 to release the mechanism for driving the shell exploding plunger into the cap of the shell. When the finger is removed from the plunger 23, the spring 24 will return it to its normal position. The breech can now be broken and a new shell put in place, and the breech closed. The gun will then again be ready for use. This gun can not be accidentally discharged since the

trigger actuating mechanism is inclosed in the stock of the gun as shown in Figs. 1 and 2 and the plunger 23 is covered by the sliding plate 28 thus preventing the gun from being discharged by the finger being brought into engagement with the plunger 23 when not desired.

I have therefore provided a gun which will be safe to handle, and which can be easily discharged.

It will also be seen that the actuating mechanism is so constructed that it is very simple and thus not liable to easily get out of working order.

15 What is claimed is:

1. A gun having its stock provided with a chamber and having a passage-way leading therefrom, the trigger of said gun extending into said passage-way, a piston slidably mounted in said passage-way, an arm extending from said piston into said chamber, and a plunger slidably mounted in said chamber and connected with said arm whereby when said plunger is moved inwardly said piston will be moved longitudinally in said passage-way to engage said trigger and actuate the same.

2. A gun having its stock provided with a chamber and with a passage-way leading therefrom, the trigger of said gun extending into said passage-way, a piston slidably mounted in said passage-way and provided with an arm extending into said chamber, and means slidably mounted in said chamber and connected with the arm of said piston whereby said piston may be moved longitudinally in said passage.

3. A gun having its stock provided with a chamber and with a passage leading therefrom, the trigger of said gun extending into said passage, a piston slidably mounted in said passage and provided with an arm extending into said chamber, a casing mounted in said chamber and provided with a slot, a plunger slidably mounted in said casing, a pivot ear extending from said plunger

through said slot and connected with said arm, and means yieldably holding said plunger in a normal position.

4. A gun having its stock provided with a chamber and with a passage-way leading therefrom, the trigger of said gun extending into said passage, a casing mounted in said chamber and provided with a longitudinally-extending slot, a plunger slidably mounted in said casing and having its outer end formed into an enlarged head limiting its inward movement, a pivot ear extending from said plunger through said slot, a piston slidably mounted in said passage and provided with an arm extending into said chamber and pivotally connected with said pivot ear, a spring mounted in said casing and engaging the lower end portion of said plunger to yieldably hold the same in a normal position, and a spring mounted in said chamber and engaging the arm of said piston.

5. A gun having its stock provided with a chamber and with a passage-way leading therefrom, the trigger of said gun extending into said passage, trigger actuating means slidably mounted in said passage, and means for operating said trigger actuating means slidably mounted in said chamber and pivotally connected with said trigger actuating means.

6. A gun having its stock provided with a chamber and with a passage leading therefrom, trigger actuating means slidably mounted in said passage and extending into said chamber, means mounted in said chamber for operating said trigger actuating means, and a movably mounted closure for said chamber.

In testimony whereof I affix my signature in presence of two witnesses.

THOMAS J. WILLIAMS.
